FASTENER INSERTING MACHINE

Frank Bycroft Keall, Leicester, England, assignor
to United Shoe Machinery Corporation, Flem-
ington, N. J., a corporation of New Jersey

Application June 13, 1945, Serial No. 599,225
In Great Britain June 29, 1944

2 Claims. (Cl. 1-18)

1

This invention is concerned with improvements in fastener inserting machines and is particularly, but by no means exclusively, concerned with machines organized to separate nails from a bulk of nails in a receptacle of the machine and to insert them one by one into a work piece.

Herein the term fastener is used as indicating not only an element to be inserted for strictly fastening purposes but also as an element which may be inserted for such purpose as wear resistance or ornamentation rather than for fastening.

By way of example, but not of limitation of the invention, there is hereinafter described one convenient construction of machine which is provided by the invention and is illustrative thereof, the illustrative machine being a machine adapted for inserting nails into shoes and having a work supporting horn, means for separating a nail from a raceway containing a row of nails, means for driving the separated nail and means for feeding the work beneath the nail driving means.

One of the various objects of the present invention is to provide a fastener inserting machine which may be operated at relatively high speed (i. e. about 600 R. P. M., or more) without undue noise.

In accordance with one feature of the invention, the fastener inserting driver of the illustrative machine is operated by crank mechanism instead of by a spring and cam as heretofore, enabling the driver to be operated without undue noise and at an increased rate of speed. Moreover, mechanism is provided for causing the fastener inserting movement of the driver to be accelerated as compared with the remainder of its movement.

In accordance with another feature of the invention the awl of the illustrative machine is carried on and operated by an arm of substantial length extending rearwardly of the machine and arranged for movement heightwise and laterally of the machine to cause the awl to pierce the work and to impart feeding movements thereto.

These and other features of the invention will now be described in detail with reference to the accompanying drawings and will be pointed out in the appended claims.

A fastener inserting machine in which the invention is shown as embodied, is illustrated in various views in the drawings in which

Figure 1 is a front elevation of part of the illustrative machine;

Figure 2 is a section on the line II--II in Figure 1;

2

Figure 3 is a right hand side elevation of awl operating mechanism of the illustrative machine;

Figure 4 is a plan view of the parts shown in Figure 3; and

Figure 5 is a left hand side elevation of nail separator mechanism of the illustrative machine.

In the illustrative machine, which is similar to the machine disclosed in United States Letters Patent No. 898,573, granted September 15, 1908, on an application filed in the name of George Goddu, the upper end portion of the driver 1 is secured by a clamping collar 3 in the lower end portion of a driver carrier 5 and its lower end portion is guided in a throat comprising a nosepiece 7 and a plate 9, corresponding respectively to the nosepiece referred to as the nosepiece E and the plate referred to as the plate 41 in said patent, which are secured to a swinging head 11 corresponding to the head referred to as the 20 swinging head B in said patent.

The upper end portion of the driver carrier 5, which is a relatively small light part, is pivotally mounted on a horizontal spindle 13 extending forwardly and rearwardly of the machine. The spindle 13 has pivoted on it the right hand end portion of a link 15 which extends upwardly and to the left from the spindle and at its other end it is pivotally connected at 17 to a crank lever 19. The right hand portion of the crank lever 19, at the right of its connection to the link 15, is pivoted on a crank pin 21 secured in the front of an arm 23 secured on the front end portion of a horizontal cam shaft 25, extending forwardly and rearwardly of the machine and corresponding to the shaft referred to as the main shaft C² in said patent. The left hand end portion of the crank lever 19 has on it a cam roll 27 which extends rearwardly from the lever and engages in a cam groove 29 in a cam block 31 secured to the machine frame.

Pivoted on the spindle 13 is a link 33 which is pivotally connected at 35 to a radius arm 31 pivoted at 39 to a bracket 41 secured on the swinging head 11. The link 33 has secured in it a stud 43 on which is rotatably mounted a roll 45 which engages an arcuate guideway 47 in a block 49 secured to the swinging head 11.

The driver carrier 5 has projecting from it lugs 51, 53. A face on the lug 51 may engage a face on a bracket 55 secured to the swinging head 11 and a face on the lug 53 may engage a face 57 on the swinging head 11. The lugs 51, 53 and faces on the bracket 55 and swinging head prevent damage to the machine, should the driver break, by uncontrolled swinging movement of the driver

carrier about the spindle 13. As the cam shaft 25 rotates the crank pin 21 causes the cam roll 27 on the crank lever 19 to travel along the cam groove 29 and the arrangement is such that as the crank pin 21 is approaching its lowest point the cam roll 27 is moving up the cam groove 29 and causes the downward movement of the driver to be accelerated so that a relatively rapid downward movement of the driver when a nail is being driven is obtained. A somewhat slower but rapid rise of the driver then occurs and when the driver is about in its highest position the driver remains more or less stationary until it is given a rapid downward movement to drive the next nail. The link 33, radius arm 37 and arcuate guideway 41 control the path of movement of the spindle 13.

The driver mechanism above described is capable of being operated at relatively high speed without undue noise or wear of the parts.

The awl 61, in the illustrative machine, is secured by a cap 63 in the forward end portion of an awl arm 65. The rear end portion of the awl arm is pivotally connected by a universal coupling, to a bracket 67 secured to the rear portion of the machine frame. The latter universal coupling is positioned so far rearwardly of the awl that up and down movements of the awl into and out of the work are substantially straight line movements.

The rear end portion of the awl arm 65 is provided with two recesses each arranged to receive a part-ball member 69 and a plate 71 secured by screws 73 to the awl arm 65 has formed on it two recesses each arranged to receive a part-ball member 75, the part-ball members 69 and 75 being in axial alignment in each instance. The bracket 67 has a plate-like portion 77 which is engaged by the flat faces of the part-ball members. Sufficient clearance is provided between the rear end portion of the awl arm and plate 71 and the portion 77 of the bracket 67 to allow the front end portion of the awl arm to move up and down about the part-ball members 69, 75.

The plate-like portion 77 of the bracket 67 has secured in it a block 79, the block having extending from it a screw-threaded stem 81 which passes through the plate-like portion 77 and is secured thereto by a nut 83. The block 79 is positioned between and engaged by two part-ball members 85 seated in recesses formed in the rear end portion of the awl arm 65 and a cap 87 secured thereto. The front end portion of the awl arm 65 can therefore move laterally of the machine when the work is fed by the awl about the part-ball members 85 and the rear end portion of the awl arm may move forwardly and rearwardly of the machine since the part-ball members 85 can slide on the block 79. The spaced apart relationship of the two sets of part-ball members 69, 75 prevents twisting of the awl bar. It will be apparent that the arrangement at the rear end portion of the awl arm provides the aforesaid universal coupling and that up and down and lateral movements of the front end portion of the front end portion of the awl arm take place about part-ball members.

In order to cause the awl 61 to move in at least a substantially straight path as it is feeding the work the awl arm 65 has formed in it a spherical recess 89 in which is a ball end 91 of a rod 93. The ball 91 is held in the recess 89 by a cap 95 secured to the awl arm and having in it a spherical recess which engages the ball 75

91. The rod 93 is secured in a member 97 having a cap 99 secured thereto. The member 97 and cap 99 have formed in them spherical recesses arranged to receive a ball 101 formed on the upper end of a spindle 103. As the front end portion of the awl arm 65 is moved in a direction to feed the work, i. e., to the left viewed from the front of the machine, the awl arm swings about the part-ball members 85 and the member 97 and the rod 93 swing about the ball 101, the arrangement being such that the swinging movement of the member 97 and rod 93 causes the awl arm 65 to move slightly forwardly, the part-ball members 85 sliding across the block 79, with the result that the front end portion of the awl arm and the awl move in at least a substantially straight path. The spindle 103 has a stem 105 which is secured by a screw 107 in a bracket 109 secured to the machine frame. The stem 105 is eccentric to the axis of the ball 101 so that if the spindle is rotated by means of a bar 111 therein the front portion of the awl arm 65 may be adjusted to adjust the awl relatively to the driver to cause during operation of the machine a hole made in the work by the awl to move into alignment with the driver.

To move the front end portion of the awl arm 65 laterally to feed the work a plate 113 is secured to a block 115 (Figure 1) secured to the swinging head. The plate 113 is engaged by flat faces on part-ball members 117 which are seated in spherical recesses formed in the front end of the awl arm and a cap 119 secured thereto.

The front end portion of the awl arm 65 has secured in it a ball-end stud 121 which is engaged by a spherical recess formed partly in the lower end portion of a link 123, and partly in a cap 125 secured to the lower end portion of the link 123. The upper end of the link is connected to a ball-ended stud 127 secured in an arm 129, which corresponds to the sector referred to as the toothed sector f^8 in the above-mentioned patent, the arm being secured on a shaft 131, corresponding to the shaft referred to as the rockshaft f^4 in said patent and is operated in the same manner as the last mentioned shaft.

The ball-ended stud 127 has a stem 133 which is secured in the arm 129 and is eccentric to the ball so that by rotating the stud 127 the height-wise position of the awl 61 may be adjusted.

It will be apparent that the awl operating mechanism of the illustrative machine comprises a number of ball joints which tend to prevent undue wear and noise and may readily be renewed.

A nail separator lever 135 (Figure 5) in the illustrative machine, corresponding to the lever referred to as the separator lever g^3 in the above-mentioned patent, and having secured on it a nail separator 137, similar to the blade referred to as the separator blade g^{3x} in that patent, is pivoted on a stud 139 extending laterally of the machine and secured in the swinging head. The nail separator lever 135 has a rearwardly extending arm 141 to which is pivotally connected, by a universal coupling indicated at 143, the lower end portion of a link 145. The link 145 extends upwardly and its upper end portion is connected by a universal joint, indicated at 147, to one arm 149 of a bell-crank lever 151 which is pivoted on a substantially horizontal stud 153 extending laterally of the machine and secured in the swinging head. The other arm 155 of the bell-crank lever 151 is connected by a rearwardly extending two-part rod 157 to a cam lever 159, similar to the arm

referred to as the arm 82 in United States Letters Patent No. 1,859,421, granted May 24, 1932, on an application filed in the name of Reginald B. Woodcock, the arm being pivoted on the machine frame. The cam lever 159 has on it a cam roll 161 which engages a face cam 163 corresponding to the cam referred to as the cam 60 in the last mentioned patent, which is rotated half a revolution during each revolution of the main cam shaft 25 of the machine. In the illustrative machine, however, the cam 163 is so arranged that the separator operates to separate a nail and deliver it beneath the driver in each cycle of the machine. The aforesaid two-part rod 157 comprises one part having a ball-shaped end which engages the bottom of a recess in the cam lever 159 and another part slidingly mounted in the first part and having a ball-shaped end which engages the end of a screw 165 in the arm 155 of the bell-crank lever 151. A spring 167 on the two-part rod tends to separate the two parts and to hold the ball-shaped ends thereof respectively in the recess in the cam lever and against the screw in the bell-crank lever. A spring 169, corresponding to the spring referred to as the spring 76 in the last mentioned patent, moves the separator forwardly to separate a nail, this movement of the separator being limited by the engagement of the separator lever with a portion of the swinging head. When the cam is moving the separator rearwardly the two-part link acts as a solid member to move the separator and when the spring 169 is moving the separator forwardly the spring on the two-part rod 157 expands the rod and holds the cam roll 161 against a low part of the cam so that the cam does not interfere with the forward movement of the separator.

The related operations of the above described awl and driver mechanisms are as follows: On rotation of the rockshaft 131 in a counterclockwise direction, as viewed in Fig. 1, the link 123 is moved downward, thereby swinging the awl arm 65 downward and causing the awl 61 to pierce the work which rests on a suitable support, this being a horn in the present case. While the awl is down and in piercing engagement with the work, the swinging head 11 is moved to the left of Fig. 1, thereby moving through the above described connections, namely the block 115 and the plate 113, the front end portion of the awl 50 arm 65 laterally of the machine to feed the work. The lateral feed movement of the awl arm ends when the awl hole made in the work by the awl is vertically aligned with the path of movement of the driver 1. While then the work remains stationary, the motion of the link 123 is reversed and thus

the awl arm 65 is moved upward, causing the awl 61 to be withdrawn from the work. Thereafter the head 11 moves toward the right of Fig. 1 into its initial position, thereby returning the awl above the surface of the work into its initial position from which its four-way motion was initiated. In the meantime a nail has been separated by the separator 137 and delivered beneath the driver 1, whereupon the driver, after the awl has been moved out of the path of movement of the driver, is actuated by the crank 21 to descend and drive the nail into the awl hole previously made and located in vertical alinement with and beneath the driver. The movement of the driver in descending is accelerated, as described, by the action of the cam groove 29 on the cam roll 27. The return of the driver 1 to its initial elevated position terminates one cycle of operations.

Having described my invention, what I claim as new and desire to secure by Letters Patent of the United States is:

1. In a fastener inserting machine, a fastener inserting driver, crank operated mechanism for actuating the driver, and means cooperating with said mechanism for accelerating the driver when on its operative fastener inserting stroke.
2. In a fastener inserting machine, a work piercing awl, a fastener inserting driver, a pivoted arm extending rearwardly in the machine and carrying the awl at its forward end, means for moving said arm heightwise and laterally of the machine to cause the awl to pierce and feed the work, crank operated mechanism for actuating the driver in time relation to the operation of the awl, and means cooperating with said mechanism for accelerating the driver when on its operative fastener inserting stroke.

FRANK BYCROFT KEALL.
